Primary Examiner — Robert M Spear*Assistant Examiner* — Marissa J Cash(74) *Attorney, Agent, or Firm* — Norton Rose Fulbright US LLP(57) **CLAIM**

The ornamental designs for bottle cap, as shown and described.

DESCRIPTION

FIG. 1 is a perspective view of a first embodiment of a transparent or translucent bottle cap shown disposed on a bottle base;

FIG. 2 is a front side view of the bottle shown in FIG. 1;

FIG. 3 is a left side view of the bottles show in FIG. 1;

FIG. 4 is a top view of the bottle shown in FIG. 1;

FIG. 5 is a perspective view of a second embodiment that differs from the first embodiment of FIG. 1 in that the bottle cap is not transparent or translucent;

FIG. 6 is a front side view of the bottle shown in FIG. 5;

FIG. 7 is a left side view of the bottles show in FIG. 5; and,

FIG. 8 is a top view of the bottle shown in FIG. 5.

The dashed lines in FIGS. 1-7 form no part of the claimed design. For example, the dashed lines in FIGS. 1-4 that are within the perimeter of the bottle cap represent certain features of the bottom of one example of the bottle cap; and the dashed lines in FIGS. 1-3 (as also in FIGS. 5-7) that are below the bottle cap represent a bottle base that is not a part of the depicted embodiments of the present designs.

All other surface(s) or portion(s) of the bottles not shown in the figures or otherwise described in the specification form no part of the claimed design.
